UNITED STATES PATENT OFFICE

162,810

PICTURE FRAME OR SIMILAR ARTICLE

George Glass, Brookline, Mass., assignor to Display Advertising Corporation, Boston, Mass., a corporation of Massachusetts

Application August 11, 1948, Serial No. 148,043

Term of patent 3½ years

(Cl. D29—20)

To all whom it may concern:

Be it known that I, George Glass, a citizen of the United States, residing in Brookline, in the county of Norfolk and State of Massachusetts, have invented a new, original, and ornamental Design for a Picture Frame or Similar Article, of which the following is a specification, reference being had to the accompanying drawing forming a part thereof, in which Figure 1 is a front perspective view of a picture frame or similar article showing my new design. The other parts of the frame are plain, and Figure 2 shows a sectional view on the line 2—2 of Figure 1.

I claim:

The ornamental design for a picture frame or similar article as shown and described.

GEORGE GLASS.
